Pierre Barnes
ATTORNEY

UNITED STATES PATENT OFFICE.

ELLIOTT M. OKINS, OF AUBURN, WASHINGTON.

LAUNDRY-MANGLE.

1,200,128.

Specification of Letters Patent. Patented Oct. 3, 1916.

Application filed December 4, 1915. Serial No. 64,975.

To all whom it may concern:

Be it known that I, ELLIOTT M. OKINS, a citizen of the United States, residing at Auburn, in the county of King and State of Washington, have invented certain new and useful Improvements in Laundry-Mangles, of which the following is a specification.

This invention relates to laundry mangles, and its object is the provision of adjustable means whereby the goods may be caused to revolve selectively one or more times about the machine cylinder.

To properly dry and iron certain kinds of goods or those of different weights and thicknesses in a mangle, it is requisite to run the work through the machine a number of times and which has hitherto been effected by returning articles from the delivery to the feeding sides of the machine to be refed thereto. In consequence of the labor, inconvenience and time required to carry the goods around the machine for a second operation, the goods have oftentimes been delivered in but a partially finished condition.

To overcome the above-mentioned difficulties, I provide a laundry mangle with a doffer-blade adapted to be adjustably moved into and out of operative position according to the demand, together with means whereby such adjustments may be readily attained by the attendant without stopping or otherwise interfering with the operation of the machine.

The invention is illustrated in the accompanying drawings, in which—

Figure 1 is a side elevational view, partly broken away of a laundry mangle provided with my invention. Fig. 2 is a fragmentary longitudinal vertical section of the same to an enlarged scale. Fig. 3 is a front elevation of parts shown in Fig. 2. Fig. 4 is a horizontal section of Fig. 2. Fig. 5 is a perspective view of one end of the doffer-blade supporting bar.

The mangle may, as regards the frame members 10, the rotary cylinder 11, an endless apron 12, the rolls therefor and the driving mechanism, be of any usual or suitable construction.

The apron 12 passes about a power-driven roll 13 in front of the cylinder and thence about the latter to a power-driven roll 13¹, from which it extends to a tightener roll 13² and returns about guide rolls 13³ to the

first-named roll 13. The driving mechanism for the cylinder and for the aforesaid power-driven rolls being at the opposite side of the machine from that illustrated in Fig. 1, is not shown.

14 represents a roll having its axle ends journaled in levers 15 which are fulcrumed at 16 to the frame-members 10. Endless ribbons 17 pass about the roll 14 and also about transversely arranged plate members 18. These members are formed with arms 19 which are hingedly connected by pins 20 to lugs 21 provided on the upright flange 22 of an angle bar 23.

24 represent doffer-blades which serve to direct articles passing about the cylinder to the ribbons and are fixedly secured to the respective plate members 18. Said blades are slotted as at 25 (Fig. 4) to afford with 75 the members 18, guide-ways for the various aprons.

According to the present invention, the bar 23 which carries the members 18 and the doffer-blades, is provided at its ends 80 with runner elements 26 arranged longitudinal of the machine frame and slidably in guides provided between bracket elements 27 and 28 provided on or secured to the frame members 10. By such devices, the bar 85 23 may be moved to carry said doffer-blades to or from the cylinder according to whether it is desired to employ the ribbons to convey the work from the cylinder after once passing around the latter onto the delivery lead of the apron or to render the aprons temporarily inoperative to cause the goods to again travel about the cylinder.

The preferred means, as illustrated, for moving the bar 23 consists in employing 95 at each end of the bar a crank-arm 29 which is connected from one end by a pivotal pin 30 to a bracket lug 28¹ and connecting the said arm at a distance from the pin 30 by a pin 31 to an end of a link 32 whose 100 other end is, in turn, connected by a pin 33 with the adjacent runner element 26 of the bar.

To withdraw the doffer-blades from the cylinder, the crank-arms 29 at both sides of 105 the machine are swung outwardly into positions such as represented in Fig. 1, to correspondingly move the bar 23 and the attached blades through the medium of the links. To restore the blades into juxtaposition with the cylinder, the crank-arms are 110 swung over to occupy the positions such as

indicated in Figs. 2 and 4, and thereby impart inward movement through the medium of the links 32 to the bar. By swinging the crank-arms to one side or the other of the pin 30, the crank-arms and the associated links are brought into locking positions with respect to the bar 23 to maintain the bar against any accidental displacement when adjusted to present the blades in either 10 operative or inoperative positions.

What I claim as my invention, is—

In a machine of the class described, the combination with a cylinder, an apron, rolls to direct the apron to convey the goods from

the front of the cylinder about the same 15 and return them to the front, ribbons and a guide roll therefor, of a doffer-blade, a support therefor, and means to move said support to carry the blade into position to co-operate with said ribbon to remove the 20 goods from the cylinder or be in position to render said ribbon temporarily inoperative.

Signed at Seattle, Washington, this 23rd day of November, 1915.

ELLIOTT M. OKINS.
